GRATE BEARER BAR

John R. Graves, Yonkers, N. Y., assignor to The Standard Stoker Company, Incorporated, New York, N. Y., a corporation of Delaware

Application April 8, 1941, Serial No. 387,455

5 Claims. (Cl. 126—168)

1

My invention relates to furnace grates for steam boiler furnaces and particularly to that type of grate in which removable grate sections are provided.

An object of my invention is to provide a novel and advantageous grate supporting construction and arrangement for a furnace fired by a stoker of the type in which the fuel conduit for at least a portion of its length extends longitudinally of the furnace beneath the furnace grate. More specifically the invention contemplates the provision of a combined stoker conduit and grate bearer bar in a stoker fired furnace of the type just described. Still more specifically the invention contemplates the provision of a combined stoker conduit and grate bearer bar frame with removable grate trunnion bearing units.

Other objects and advantages of the invention residing in the construction, combination and arrangement of parts, will be apparent, to those familiar with the art, from the following description when read in connection with the accompanying drawing, in which

Fig. 1 is longitudinal vertical central section through a locomotive firebox, in which the center grate bearer bar is formed as a part of a stoker conduit; the stoker and center grate bearer bar being shown in elevation with parts broken away and shown in section;

Fig. 2 is a sectional view taken on the line 2—2 of Fig. 1 with the grate trunnion removed.

Fig. 3 is a sectional view taken on the line 3—3 of Fig. 1; and

Fig. 4 is a sectional view taken on the line 4—4 of Fig. 1.

The invention has been shown and described as applied to a locomotive firebox but it will be apparent to those familiar to the art, that the novel grate bearer bar construction is equally applicable to various types of marine fireboxes and other boiler fireboxes.

In the drawing, a locomotive firebox of conventional form is designated by the numeral 49 and it is defined by the hollow rear wall 50, the hollow front wall 51, hollow side walls (not shown), and the grate 53. The grate 53 comprises a plurality of grate sections, indicated by the numerals 48 in Figure 4, provided with grate trunnions 68, permitting rocking movement of the grate sections 48 by suitable means, not shown. A stoker, represented generally by the numeral 52, delivers fuel to the firebox and scatters it over the grate 53.

The stoker includes a conduit 54 extending for-

2

wardly beneath the firebox backwall 50 into the lower portion of the firebox below the level of the grate 53. An elbow shaped upturned conduit 55 communicates with the forward end of the conduit 54 and extends forwardly and upwardly to a point above the level of the grate 53 and adjacent the firebox front wall 51. Suitable conveying mechanism, well known in the art, carries the coal forwardly from the tender (not shown) to the conduit 54, through which conduit the coal is advanced by a screw conveyor 56. The coal is forced through the conduit 55 and upon emerging from the discharge end thereof is projected rearwardly across the firing table 58 onto the grate 53, by suitable means, as by a blast of fluid under pressure issuing from a jet head 57 disposed at the upper forward end of the conduit 55.

The stoker conduit 54 is provided with a superstructure 59 including a longitudinally extending horizontal plate 60 spaced above the conduit 54 and joined with the conduit proper by a plurality of spaced transversely extending webs 61. Every other pair of webs 61 are joined by a pair of laterally spaced longitudinally extending webs 62 that also join the plate 60 with the conduit proper.

The plate 60 is provided throughout its length with a plurality of equally spaced longitudinally elongated slots 63 opening into the pockets 64 formed by the transverse and longitudinal webs 61 and 62. Trunnion bearing units 65 are provided on their under sides with the depending longitudinally elongated tongues 66 which are arranged to be received in the pockets 64 when the trunnion bearing units 65 are seated on the plate 60. The walls 61, 62 of the pockets 64 prevent any substantial longitudinal, lateral and rotational movement of the trunnion bearing units 65. The trunnion bearing units 65 are provided in their upper surface with the laterally extending recessed bearings 67 in which are journaled the grate trunnions 68.

The elbow-shaped conduit 55, which is supported from the boiler mud ring 69 by a bracket 70, is provided on each side with a plurality of laterally extending webs 71. To the outer ends of the webs 71 are secured, in any suitable manner, longitudinally extending plates 72, to which in turn longitudinally extending brackets 73 are suitably secured. The brackets 73 are arranged with the plates 72 to form longitudinally extending grooves in which the tongues 74 of the trunnion bearing units 75 are received. The trunnion bear-

ing units 75 are similar to the units 65 split in half vertically along their longitudinal center lines, as best shown in Fig. 4. Recessed bearings 76 in the trunnion bearing units 75 are arranged to receive the grate trunnions 68.

A protecting grate 78 embraces the upper end of the conduit 55 and is seated on the plates 72. The protecting grate 78 may be of any desirable form and provides protection for the conduit 55 from the intense heat of the firebox. The removable trunnion bearing units 65 and 75 are preferably made of cast iron, while the stoker conduit is preferably made of steel.

I claim:

1. As a new article of manufacture, a combined stoker conduit and grate bearer bar frame comprising in an integral structure a tubular stoker conduit, a plate spaced from and extending lengthwise of said stoker conduit and ribs connecting said plate and stoker conduit, said plate being formed with a plurality of slots spaced lengthwise of said plate.

2. The combination in a firebox, of a stoker conduit extending longitudinally thereof, a longitudinally extending horizontal plate spaced above and formed with said conduit, and a plurality of separable grate trunnion bearing members supported on said plate, said members being disposed in end to end abutting relation.

3. The combination in a firebox, of a stoker conduit extending longitudinally thereof, a longitudinally extending horizontal plate spaced above and formed with said conduit, said plate being formed with a plurality of slots spaced lengthwise of said plate, and separable grate trunnion bearing members having depending tongues arranged to be received in said slots upon seating said bearing members on said plate.

4. The combination in a firebox, of an integral cast steel stoker conduit and grate bearer bar frame extending longitudinally of the firebox and a plurality of separable cast iron grate trunnion bearing members supported on said frame.

5. The combination in a firebox, of a stoker conduit extending longitudinally thereof, a longitudinally extending horizontal plate spaced above and formed with said conduit, said plate being formed with a plurality of slots spaced lengthwise of said plate, and separable grate trunnion bearing members having depending tongues arranged to be received in said slots upon seating said bearing members on said plate, each of said bearing members being provided in its upper surface with a transversely extending recess adapted to receive a grate bar trunnion.

JOHN R. GRAVES.
